CONNECTING ROD

Roland Chilton, Ridgewood, N. J., assignor, by
mesne assignments, to The Reed Propeller Co.,
Inc., Garden City, N. Y., a corporation of New
York

Application June 1, 1934, Serial No. 728,481

8 Claims. (Cl. 74—580)

This invention relates to connecting rods for radial engines and comprises a new and improved form of the slipper type rod.

The well known master rod and link rod construction for radial engines has offset knuckle pins which follow elliptical paths which introduce variations in the angularities of the different rods and upset the engine balance and the piston travel relationships. The slipper design, 10 wherein each rod engages an annular track in a crankpin bearing member, gives uniform motion of the pistons.

In order to guard against binding of the slippers in their tracks, a substantial arc of embracement for each slipper is essential and the required circumferential slipper length is greater than the space available when several slippers of simple rectangular form are disposed in a common track. The prior art shows various 20 double track schemes for obtaining a greater effective arc of embracement, and diagonally disposed slippers have been proposed for the same purpose. The double tracks are relatively expensive to produce and tend to weaken the 25 bearing member as compared to the simpler single track. The diagonally disposed slipper fails to guide the rod adequately against tipping at right angles to the long diagonal axis of the slipper.

Objects of the present invention are to provide a simplified structure which will overcome these limitations as will be clear from the following description.

In the drawings:

Fig. 1 is a section through the crankpin axis showing one rod in complete section;

Fig. 2 is an isometric detail view showing the form of slipper;

Fig. 3 is an end view with certain parts in section; and

Fig. 4 is a developed diagram showing the slipper disposition.

In the figures, 10 designates the crankpin bearing member comprising similar halves opposed on either side of the transverse midplane of the assembly. A crankpin 12 has been shown as integral with crankshaft webs 14 in which case the bearing members 10 are split in the plane of the crankpin axis and secured together 50 by bolts 16. Each of the members 10 is provided with an annular groove 18 in which are disposed the several slippers 20 of rods 22.

The permissible annular width of each main slipper portion 20 is determined by the number 55 of rods and by the clearance necessary to per-

mit of relative motion. With six rods, for example, the limited arc of embracement is insufficient to insure against binding of the slippers in the tracks, and according to this invention each slipper is provided, on one side, with relatively narrow guiding extensions 24 and the rods are assembled with these extensions on alternate sides as indicated clearly in Fig. 4. It will be obvious that the annular length of slipper in the case of six rods is only one-half of that available with three rods and that by the novel disposition of this invention the length available for the guiding extensions is that obtainable in a conventional three rod construction, although six rods are actually accommodated.

It will be understood that the main portion 20 of the slippers are of symmetrical disposition so that the loads on the extensions 24 are merely those incident to guiding the rods circumferentially. These light loads may generate a slight twisting tendency on the rod for which a relatively wide guiding surface 26 is accordingly provided in the rod shank, this surface engaging the opposed outer faces 28 of the bearing members 10.

The bearing members 10 are provided with a bushing 30 which runs on the crankpin 12 and behind this bushing there are provided, in the members 10, a plurality of oil holes 32, in which are engaged small valves 34, which are lifted slightly off their seats whenever the associated oil hole is covered by one of the slippers 20. Whenever the oil hole passes into the space between adjacent slippers, the associated valve 34 closes by the action of centrifugal force and oil pressure, thus preventing loss of oil when the holes are uncovered. It will be clear that when the valve is on its seat the end protrudes slightly beyond the surface in the track to permit the automatic actuation from the slippers as just described. By this means it is possible to provide for full pressure lubrication to the slippers without excessive loss of oil, which occurs when holes subject to oil pressure are left open, as in the spaces between the slippers. The interior of the crankpin 45 12 is subject to oil pressure in the usual way and the oil flows by way of the oil holes 36 in the crankpin and holes 38 in the bearing member 10, to suitable grooves 40 which connect to the valves.

It will be seen that by the novel form of slipper here disclosed a long arc of guiding embracement is provided in a simple single track bearing member permitting twice the arc of guiding slipper than would be possible in conventional single track construction. Also, the slippers are in rec- 55

tilinear relationship, eliminating the twisting forces that are normally imposed on the rod when using diagonally formed slippers.

While I have described my invention in detail 5 in its present preferred embodiment, it will be obvious to those skilled in the art, after understanding my invention, that various changes and modifications may be made therein without departing from the spirit or scope thereof: I aim in 10 the appended claims to cover all such modifications and changes.

What is claimed is:

1. A radial engine connecting rod system including a pair of bearing members having opposed 15 and similar annular tracks, and a plurality of rods each having a main slipper engaging both tracks and a guide slipper extending axially and circumferentially from the main slipper, each rod having its guiding slipper engaged in one said 20 track, the guide slippers of rods adjacent thereto being engaged in the opposite track, each said guide slipper having an arc of track embracement substantially twice as great as the arc of track embracement of each main slipper, and overlapping 25 the main slipper of an adjacent rod.

2. A slipper rod system for use with a crankpin having opposed annular tracks, each rod comprising a shank, a main slipper portion carried by said shank and substantially coaxial with the 30 rod, said portion engaging both said tracks, and auxiliary guiding slipper portions springing from said main portion and engaging one said track, said auxiliary slipper portions having a greater arc of bearing contact than said main slipper portion, and being axially offset therefrom, the adjacent rods having their guiding slipper portions in opposite tracks, the guiding slipper portions of each rod overlapping the main slipper portions of adjacent rods.

3. In a rod system for a radial engine, a pair of annular opposed tracks, a plurality of similar rods having bearing slippers engaging said tracks, and guiding slipper portions extending axially and circumferentially from each said slipper, the 45 guiding slipper portion of each rod engaging one said track, the guide slippers of rods adjacent thereto being engaged in the opposite track, each said guide slipper overlapping the bearing slippers of adjacent rods.

4. In a rod system for a radial engine; a pair of opposed bearing members, having opposite, similar, annular tracks therein; and a plurality of similar connecting rods each having a main bearing slipper engaging both said tracks, the mid- 55 portion of said slipper being substantially coaxial with the rod axis and said slipper being substantially symmetrical on each side of the plane of rod rotation, and an auxiliary guide slipper extending axially and circumferentially from said main slipper, said guide slipper having a greater arc of track embracement than said

main slipper, each said guide slipper engaging within one said track, and guide slippers adjacent thereto engaging within the other said track.

5. In a rod system for a radial engine; a pair of opposed bearing members, having opposite, similar, annular tracks therein; and a plurality of similar connecting rods each having a main bearing slipper engaging both said tracks, the mid- 10 portion of said slipper being substantially coaxial with the rod axis and said slipper being substantially symmetrical on each side of the plane of rod rotation, and an auxiliary guide slipper extending axially and circumferentially from said main slipper, said guide slipper having a greater arc of track embracement than said main slipper, each said guide slipper engaging within one said track, and guide slippers adjacent thereto engaging within the other said track, the guide slippers of any one rod overlapping the main 15 slippers of adjacent rods.

6. A slipper rod system for a radial engine comprising a member having opposed annular tracks and rods each having a main slipper engaging each of said tracks, each of said rods having guiding slipper portions extending in circumferential symmetry from one end only of said main portion and engaging only one of said annular tracks, the adjacent rods of the system having their guiding slipper portions engaged in opposite tracks and each overlapping the next 20 adjacent main slippers.

7. A rod system for a radial engine each rod including main and auxiliary slipper portions having outer and inner bearing surfaces, the outer surfaces of both said main and auxiliary portions 35 having the same radius, and the inner surfaces of both said main and auxiliary portions having the same radius, the auxiliary portions extending in circumferential symmetry from the main portion on one side only of the plane of rotation, and each guide slipper overlapping the main slipper of a next adjacent rod.

8. A radial engine connecting rod system including, in combination, a pair of bearing members having opposed similar annular tracks, a main symmetrical slipper on each rod engaging both tracks, and a guide slipper formed as an extension of each main slipper, said guide slipper being axially spaced from the plane of rod rotation, and extending circumferentially beyond both 50 ends of its associated main slipper, the guide slippers on adjacent rods being assembled in staggered relation in said bearing members, said main slippers each having a circumferential dimension substantially equal to the track circumference 55 divided by the number of rods, and each said auxiliary slipper having a circumferential dimension substantially equal to twice the circumferential dimension of each said main slipper.

ROLAND CHILTON.
